Primary Examiner—Bruce W. Dunkins*Assistant Examiner*—Martha Thompson*Attorney, Agent, or Firm*—Richard P. Crowley**[57] CLAIM**

The ornamental design for an adjustable document holder clip, as shown and described.

DESCRIPTION

FIG. 1 is a front perspective view of an adjustable document holder clip showing my new design, the typewriter fragment being depicted by means of broken lines for illustrative purposes only and forming no part of the claimed design;

FIG. 2 is a top plan view;

FIG. 3 is a front elevational view;

FIG. 4 is a left side elevational view;

FIG. 5 is a right side elevational view; and,

FIG. 6 is a bottom plan view thereof.

FIG.1

FIG.2
